UNITED STATES PATENT OFFICE.

CHARLES EDWARD HAVILAND, OF LIMOGES, FRANCE.

DESIGN FOR A CUP.

SPECIFICATION forming part of Design No. 17,059, dated January 11, 1887.

Application filed November 20, 1886. Serial No. 219,524. Term of patent 14 years.

To all whom it may concern:

Be it known that I, CHARLES EDWARD HAVILAND, a citizen of the United States, residing at Limoges, in the Republic of France, have 5 invented and produced a new and original Design for Cups, which is described and represented in the following specification and accompanying fac-similes, forming a part of the same.

10 Figure 1 is a perspective view of a cup embodying this design, and Fig. 2 is a diagram showing its horizontal conformations at different vertical heights.

15 The characteristic features of the design are a circular top, A, a polygonal body, B, and a circular foot, C, substantially as shown in the accompanying fac similes.

The body of the cup is gradually shaped as the bottom is approached, to form slight in-

ward curves, elongated at 1 and abrupt at 2, 20 between which are outward curves 3, thus producing a polygonal contour, as is best shown in Fig. 2. From a point near the bottom the body B is rather abruptly bent inwardly to join the foot C, still preserving the 25 polygonal contour.

What I claim is—

The design for cups, the same consisting of the circular top, polygonal body formed by curves, and a circular foot, substantially as 30 shown and described.

In testimony whereof I have hereunto set my hand in the presence of two subscribing witnesses.

CH. ED. HAVILAND.

Witnesses:

F. CATE,
A. SENÉQUE.
